UNITED STATES PATENT OFFICE.

JOSEPH A. ROSS, OF NANTICOKE, PENNSYLVANIA, ASSIGNOR OF ONE-HALF TO WILLIAM L. DELANEY, OF SHEATOWN, PENNSYLVANIA.

PURSUIT TOY.

Application filed December 28, 1923. Serial No. 683,219.

This invention relates to amusement devices and more particularly to an amusement device wherein a figure in the form of a policeman is represented as pursuing a second figure in the form of a negro or any fugitive.

Briefly stated an important object is to provide an amusement device of the character specified in which novel means is provided to periodically expose the fleeing figure in advance of the pursuing figure and to cause the fleeing figure to turn in the direction of the pursuing figure and then cause the fleeing figure to disappear, all of which is accomplished by the simple turning of a crank by hand, a spring motor or by any suitable means.

A further object is to provide an amusement device which is of highly simplified construction, durable in use and cheap to manufacture.

Other objects and advantages will be apparent during the course of the following description.

In the accompanying drawing forming a part of this application, and in which like numerals are employed to designate like parts throughout the same,

Figure 1 is a plan view of the improved amusement device.

Figure 2 is a side elevation of the amusement device.

Figure 3 is a fragmentary plan view illustrating the positions the parts assume during the exposure of the fleeing figure and immediately before the fleeing figure turns its head.

Figure 4 is a detail view illustrating the means to swing the arms and legs of the pursuing figure.

Figure 5 is a detail elevation illustrating the standard for supporting the pursuing figure and the means to operate the arms and legs of the pursuing figure.

Figure 6 is a fragmentary elevation taken at right angles to Figure 5.

Figure 7 is a detail view illustrating the position the parts assume during the exposure of the pursuing figure.

Figure 8 is a detail view illustrating a lever embodied in the invention, and

Figure 9 is a fragmentary sectional view showing the rotatable drum and its associated parts.

In the drawings wherein for the purpose 55 of illustration is shown a preferred embodiment of the invention the numeral 5 designates a casing, the top 6 of which is formed with marks by which the top may be made to represent the intersection of 60 two streets. Figure 2 illustrates that a traffic signal 7 is mounted on the center of the casing at the intersection of the streets and may be operated by means of a handle 8.

An officer or pursuing figure 9 operates 65 in a circular path and is supposed to be in search of a fleeing figure 10. Figure 7 illustrates that the figure 10 is in the form of a negro, and the negro appears at times from beneath man-hole covers 11.

The fugitive figure is mounted upon a radial arm 14 rotatably mounted at its inner end on a pivot element 15. The pivot element 15 is extended through a drum 16, the upper end of which rotatably supports 70 oppositely located horizontally arranged pivot elements 17. The pivot elements 17 in turn support actuating levers 18, the intermediate portion of each actuating lever being provided with an upstanding lug 19.

Each upstanding lug 19 is adapted to engage a depending lug 20 on one longitudinal edge of a figure supporting arm 22. The figure supporting arm is also mounted on the pivot element 15 and when the drum 16 is rotated by means to be later described, the levers are moved about the axis of the pivot element 15 so that one of the levers and more particularly the lug 19 of the same is engaged with the depending lug 20 of the 80 arm 22. Therefore the arm 22 is so mounted that the laterally projecting branch 24 on the arm 22 will engage the rearwardly projecting branch 25 of the head turning lever 26 pivoted as at 26^a to the arm 14.

When the branch 24 is engaged with the branch 25 the pivoted head 29 of the figure 10 is turned about a quarter of a turn in the direction of the pursuing figure 9. This is brought about by a crank 28 extended vertically through the body 10 and having connection with the lever 26 and the head 29.

The lower portion of the crank is received in a slot 30 and when the lever 26 is actuated the head 29 is turned about a quarter of a turn. However the swinging movement of the lever 26 is limited by upstanding stop members 31 carried by the rear end of the lever and adapted to engage the opposite longitudinal edges of the arms 14. Immediately after the turning of the head 29 by the means just described, the releasing arm 33 engages the lifting bracket 35 and moves the same laterally a limited extent so that the figure carrying arm 14 may drop. It might be stated at this point that during the movement of the arm 14 about the axis of the pin 15 it engages the inclined upper edge 36 of the bracket 35 and consequently the figure 10 is lifted so that it moves through an opening beneath the man-hole cover 11. When the arm 14 reaches the limit of its upward movement on one of the brackets 35 it is engaged in a notch 40 and is held in this position. As the arm 14 is lifted into the notch 40 by the camming bracket 35, this arm 14 is disengaged from the lever 18 since this arm 14 is raised above the lever. However, when the inwardly curved end of the arm 33 forces the bracket 35 laterally, the arm 14 is released so that the figure 10 may drop to the bottom of the casing and out of sight. The arm 14 consists of an inner short section 14^a rotatably mounted on a bushing 15^a fitted on a pivot pin 15 and an outer long section 14^b connected to the section 14^a by a hinge 14^c shown in dotted lines in Figure 3. The outer long section 14^b while rotating about the pivot 15 with the inner short section 14^a is free to swing relative thereto in a vertical plane. The fleeing figure is mounted on the outer end of this long section 14^b. Each of the covers 11 may be spring actuated so that as soon as the figure 10 disappears, the covers will return to their closed position. It is also important to note that at just about the time the arm 33 forces the bracket laterally, the downwardly curved terminal portion 41 of the lever 18 is engaged with the adjacent portion of the section 14^b of the arm 14 adjacent the inner end of the section 14^b; so that this lever 18 is swung on its axis and the lug 19 of the same is released from engagement with the lug 20. Thus the lever 18 that has driven the arm 22 now drives the arm 14.

The arm 22 which carries the pursuing figure remains in the position in which it was left until the other lever 18 engages the same and carries the lever around to a position behind the arm 14. Figure 8 illustrates that the rear portion of each lever 18 is bent upon itself to define a pocket adapted for the reception of a weight 43 of any material such as lead.

During the movement of the pursuit fig-

ure 9 the arms 50 and legs 51 of the same are swung back and forth by means of a vertically movable operating rod 52. Figure 5 illustrates that the intermediate portion of the rod 52 is provided with laterally projecting shoulders or branches 54 having slots 56 to slidably receive pins 57. The pins 57 have connection with the legs 51 and it will be seen that during the up and down movement of the rod 52 the legs will be swung back and forth so that it appears as if the movement of the legs result in the travel of the pursuit figure.

Figures 5 and 6 also illustrate that the upper portion of the arm 52 is provided with a lateral branch 59 having a slot 60 for the reception of a crank 61 of an arm operating shaft 62. During the up and down movement of the pitman 52 the arms 50 are swung after the manner of the arms 85 of a person who is running.

In carrying out the invention, a friction wheel 65 is rotatably mounted on the arm 22 by means of a shaft 66 and the periphery of the wheel has frictional contact with the disk 67 set in the top of the casing. Therefore when the arm 22 is moved the friction wheel 65 will engage the underside of the disk 67 and the crank pin 69 secured to the wheel 65 is moved in an annular path so that the lower portion of the pitman rod which is connected to the pin 69 is reciprocated. As previously stated the reciprocation of the pitman rod 52 results in the rocking of the arms 50 and legs 51 of the 100 pursuit figure.

The levers 18 are moved in a circular path by the operation of a hand crank 70 clearly illustrated in Figure 3. The inner end of the shaft 71 to which the crank 70 is connected is provided with a small gear 72 which meshes with a spur gear 73 on the lower end of the drum or hub 16.

The gear 73 is supported in a raised position by means of the struck up central portion 75 of a base 76.

Attention is especially directed to Figure 3 which illustrates that the base 76 is provided with bearing members 78 to guide the shaft 71.

In operation, the crank 70 is turned so as to rotate the drum 16 and the depending lug 20 of the arm 22 will be engaged by the upstanding lug 19 of the lever 18 immediately behind. The cycle may be started with the figure 10 appearing in one of the man-holes beneath what represents the street and as the figure 9 approaches the laterally projecting branch 24 engages the rearwardly projecting branch 25 so that the head 29 is turned slightly in the direction of the pursuit figure 9. This is accomplished by the turning of the crank 28. At this point the releasing arm 33 engages the bracket 35 holding the figure 10 in exposed position 130

and the figure 10 immediately drops beneath the street. As the arm 22 continues to advance due to the more or less constant rotation of the shaft 71, the downwardly projecting forward terminal portion 41 of the lever 18 is engaged by the arm 14 so that the lever is swung downwardly for releasing the lug 19 from driving engagement with the depending lug 20. Therefore the 10 pursuit figure 9 remains in a fixed position until the diametrically opposite lever 18 is moved around to engage the lug 20.

When the figure 10 comes beneath the 15 surface the constantly moving lever 18 engages the arm 14 and more particularly the lug 19 engages the rear edge of the arm 14 so as to move the fleeing figure in a circular path.

As the figure 10 is moved in a circular 20 path the same engages the opposite bracket 35 and the figure is raised so that it appears above the surfaces directly across from the position occupied by the pursuit figure 9. When the fleeing figure 10 again appears 25 one of the levers 18 are in position to again operate the arm 22 so that it appears that the pursuit figure 9 again takes up the chase.

However immediately prior to the elevation 30 of the fleeing figure 10 by the bracket 35 the head turning lever 26 is straightened or turned back by its engagement with a projection 80 on the bottom wall of the casing.

At this point it should be remembered that 35 the lever 26 has its outer portion travelling in advance of the outer portion of the arm 14 due to the fact that this lever 26 has been shifted on its pivot 26^a by the co-action of the wings 24 and 25 as hereinabove described. Due to the fact that the outer end of this 40 lever 26 is in advance of the corresponding portion of the arm 14 and to the fact that this lever 26 is on the under side of the arm 14 it will be engaged by the projection 80 and shifted back to the position shown in 45 Fig. 3. As a consequence of this action, the fleeing figure when lifted through the next opening in the casing will be looking away from the policeman or pursuing figure and will not be turned around to face the policeman or pursuing figure until the wings 24 and 25 again come into engagement.

Briefly, the improved toy is operated by 50 a crank, spring motor or any other driving means and a policeman is represented as trying to catch a negro who is going around under the pavement, and when he thinks the policeman is not close, he looks up through one of the man-holes, just as the policeman is about to hit him, the negro looks around 55 and spies the officer and ducks beneath the surface.

When the negro disappears beneath the 60 surface, the officer stops still waiting for the negro to again appear. As previously 65 stated, the negro again appears diagonally

across from the position occupied by the officer and the officer again takes up the chase, only to be eluded by the fleeing figure ducking into the man-hole.

This cycle is continued as long as the shaft 70 75 71 is turned.

Having thus described the invention, what is claimed is:—

1. A toy comprising a rotatable drum, a pair of figure supporting arms mounted to rotate about the axis of the drum, a pair of driving levers pivoted to the drum, inter-engaging lugs on the driving levers and arms, said lugs when engaged serving to drive the arms from the lever and when disengaged permitting the arms to remain stationary, releasable holding means for holding one of said arms stationary, means on the other arm for releasing said holding means, a fleeing figure mounted on one arm 85 and a pursuing figure mounted on the other arm.

2. A toy comprising driving means including a rotatable driving element, a pair of independently rotatable figure supporting arms, a pair of levers pivoted on said driving element, releasable inter-engaging means between the levers and the arms, releasable means for holding one of said arms stationary and means on the other arm for releasing 95 said holding means.

3. A toy comprising a casing, a pivoted element, a drum rotatable about the pivot element, a pair of arms rotatable about the pivot element, one of said arms consisting of hinged sections, a pair of levers pivotally mounted on the drum and having lugs and also having inclined portions cooperable with one of said sections, said arms having lugs engageable with the lugs of said levers, a fleeing figure mounted on one of the hinged sections, said casings having spaced openings through which the figure may be elevated, camming elements connected to the casing and cooperable with the hinged section of said arm for elevating said section and the fleeing figure thereon through said openings, a pursuing figure mounted on the rigid arm and a releasing element carried by the rigid arm and engageable with the 100 105 camming element to disengage the same from the hinged arm and means for turning the drum.

4. In a toy, a casing, a pivot element mounted on the casing, a drum rotatable about the pivot element, a fleeing figure supporting arm loosely mounted on the pivot element and made up of hinged sections, a pursuing figure supporting arm and loosely mounted on the pivot element, a fleeing figure mounted on the fleeing figure supporting arm, a pursuing figure mounted on the pursuing figure supporting arm, a pair of levers pivotally mounted on the drum and having inclined portions engageable with a hinged 110 115 120 125 130

- section of the fleeing figure supporting arm and also having lugs, said arms having lugs engageable with the lugs of the levers, a pair of camming brackets mounted on the casing and cooperable with the hinged section of the fleeing figure supporting arm for elevating the same and holding the same elevated, a release bar carried by the pursuing figure supporting arm and cooperable with camming brackets for disengaging them from the hinged section of the arm with which they co-act, means for mounting the fleeing figure on its arm for turning movement, and means for turning the figure.
5. In a toy, a casing, a pivot element mounted on the casing, a drum rotatable on the pivot element, a fleeing figure supporting arm loosely mounted on the pivot element, and made up of hinged sections, a pursuing figure supporting arm and loosely mounted on the pivot element, a fleeing figure mounted on the fleeing figure supporting arm, a pursuing figure mounted on the pursuing figure supporting arm, a pair of levers pivotally mounted on the drum and having inclined portions engageable with a hinged section of the fleeing figure supporting arm and also having lugs, said arms having lugs engageable with the lugs of the levers, a pair of camming brackets mounted on the casing and cooperable with the hinged section of the fleeing figure supporting arm for elevating the same and holding the same elevated, a release bar carried by the pursuing figure supporting arm and cooperable with the camming brackets for disengaging them from the hinged section of the arm with which they co-act, means for mounting the fleeing figure on its arm for turning movement and means for turning the figure comprising cooperable wings carried by the arms and an abutment carried by the casing.
6. In a toy, a fleeing figure, a pursuing figure, driving means for moving the figures, holding means for arresting the motion of the fleeing figure to permit the pursuing figure to catch up on the fleeing figure, means for releasing the holding means when the pursuing figure has about caught up on the fleeing figure, and means for disconnecting the drive means from operative connection with the pursuing figure at a predetermined period when the pursuing figure has about caught up on the fleeing figure.
7. In a toy, a fleeing figure, a pursuing

figure, means for successively moving the figures to cause the pursuing figure to catch up on the fleeing figure and then the fleeing figure to outdistance the pursuing figure and means for turning the fleeing figure when the pursuing figure catches up with the same.

8. In a toy, a casing having openings, a fleeing figure, means for mounting the fleeing figure to permit it to appear through the openings and then disappear there-through, a pursuing figure, means for mounting the pursuing figure for movement in a path intersecting the openings, and means for successively moving the figures to cause the pursuing figure to catch up on the fleeing figure and then the fleeing figure to outdistance the pursuing figure.

9. In a toy, a casing having openings, a fleeing figure, means for mounting the fleeing figure to permit it to appear through the openings and then disappear there-through, a pursuing figure, means for mounting the pursuing figure for movement in a path intersecting the openings, means for successively moving the figures to cause the pursuing figure to catch up on the fleeing figure and then the fleeing figure to outdistance the pursuing figure and means for turning the fleeing figure when the pursuing figure catches up with the same.

10. A toy of the character specified comprising a pivoted arm movable about a vertical axis, a standard mounted on the arm, a figure connected to the standard and having pivoted arms and legs, a pitman rod having laterally projecting branches connected to said arms and legs, a friction wheel having connection with said pitman and a casing having a top wall engaged with said friction wheel whereby to turn the same, and means in the path of travel of said arm for periodically lifting the same.

11. A toy of the character specified comprising a casing having a top wall provided with an annular slot, an arm having a standard movable through said slot, a pursuit figure carried by said standard, means to turn said arm about a vertical axis, a fugitive figure movable in advance of said pursuit figure, and having an arm supporting the same, means to periodically raise the fugitive figure, and means operated by the arm of the pursuit figure to periodically drop the fugitive figure beneath the top wall of the casing.

JOSEPH A. ROSS.
